UNITED STATES PATENT OFFICE.

ELLWOOD IVINS AND WILLIAM GRIFFITHS, OF PHILADELPHIA, PENNSYLVANIA; SAID GRIFFITHS ASSIGNOR, BY DIRECT AND MESNE ASSIGNMENTS, OF THREE-FOURTHS TO SAID IVINS AND GEORGE I. COOK, OF NEW YORK, N. Y.

SEAMLESS-TUBE-ROLLING MACHINE.

SPECIFICATION forming part of Letters Patent No. 651,714, dated June 12, 1900.

Application filed February 10, 1900. Serial No. 4,738. (No model.)

To all whom it may concern:

Be it known that we, ELLWOOD IVINS and WILLIAM GRIFFITHS, citizens of the United States, residing at Philadelphia, in the county 5 of Philadelphia, State of Pennsylvania, have invented new and useful Improvements in the Manufacture of Seamless Tubes, of which the following is a specification.

Our invention relates to apparatus for forming tubes from ingots, blanks, or billets of steel or other metal wherein are employed drawing and compressing rolls and a central piercing-mandrel, the ingots, blanks, or billets being passed endwise between the adjacent working faces of said rolls and being pierced centrally and operated on interiorly by said mandrel, and has for one object to combine with said drawing and compressing rolls and mandrel a supplemental mandrel 20 and a series of supplemental rolls for further treating the tubes at one operation to remove the spiral convolutions formed therein by the piercing operation and at the same time, if desired, to reduce the thickness of 25 the walls of said tubes, said supplemental rolls being preferably the same in configuration and relative arrangement as the drawing and compressing rolls.

Still another object of our present invention is to provide improved means for cooling the conical point of the piercing-mandrel, which we accomplish by forming the same and its supporting-shaft hollow and passing therethrough a stream of cooling liquid, preferably water, novel means being employed for supplying the cooling liquid without interfering with the passage of the tubes over the mandrel.

In the accompanying drawings, Figure 1 is 40 a side elevation of our improved rolls and piercing-mandrel. Fig. 2 is a top plan view of the same. Fig. 3 is a vertical sectional view taken on the line $x-x$, Fig. 1. Fig. 4 is a top plan view showing the piercing-mandrel and rolls arranged to the rear thereof. Fig. 5 is an enlarged detail sectional view of the piercing-mandrel and its shaft, showing

the means for cooling the point of said mandrel. Fig. 6 is a similar and still more enlarged view, at a right angle to Fig. 5, of the rear end of the interior liquid-supply tube for said mandrel and its connected liquid-supply pipe.

Similar numerals of reference denote corresponding parts in the several views.

In the said drawings, referring more particularly to Figs. 1, 2, and 3, the reference-numerals 1, 2, and 3 denote the three barrel-shaped rolls, the same being mounted on the shafts 4, 5, and 6, respectively, and adapted to rotate in unison in the direction of the arrows. It will be observed by reference to Fig. 1 that the shaft 4 of roll 1 lies in a horizontal plane, while the shafts 5 and 6 of rolls 2 and 3 are inclined at opposite angles to the horizontal, the angle of shaft 5 being upward from left to right, while that of shaft 6 is downward in the same direction. By referring to Fig. 2, however, it will be observed that none of said shafts lies in a vertical plane parallel with the piercing-mandrel 7, which is located at the point of intersection of said rolls, as shown, the shaft 4 of roll 1 inclining to one side of said plane, while the shafts 5 and 6 of rolls 2 and 3 incline to the opposite side, although lying parallel with each other.

In Fig. 4 we have illustrated in connection with the piercing-mandrel 7 and its rolls 1, 2, and 3 the mechanism for removing the spiral convolutions and, if desired, for reducing the walls of the tubes, the same consisting of a series of supplemental rolls 8, 9, and 10, corresponding in configuration and relative arrangement to and rotating at the same speed with rolls 1, 2, and 3, and operating on the tubes formed by mandrel 7 and rolls 1, 2, and 3, a supplemental mandrel 11 being mounted on the shaft 12, carrying mandrel 7, and being located at the point of intersection of said supplemental rolls to provide the necessary internal resistance for the tubes. Said supplemental mandrel is of an even diameter throughout its working surface corresponding to the greatest diameter of the con-

ical piercing-mandrel 7, its front end being slightly beveled at 13 to permit the ready passage of the tubes thereon.

In Figs. 5 and 6 is shown the internal construction of the piercing-mandrel 7 and its shaft 12 for cooling the former, said shaft and mandrel being formed hollow and having inserted therein a tube 14, extending the length of said shaft 12 and terminating within the hollow interior of mandrel 7. At its rear projecting end said tube is formed with a conical seat to receive the angular extension 15 of a liquid-supply pipe 16, said parts being detachably retained together by a metallic strap 17, pivoted at 18 to pipe 14 and adapted to embrace the outer inclined end of extension 15 with a wedging action to firmly retain the parts together, as will be readily comprehended, it being understood that supply-pipe 16 may be formed of flexible material or may be rigid and have a hinged connection with its supply source (not shown) to permit its being swung down out of the path of travel of the tubes as they pass over the rear end of shaft 12, the strap 17 having been previously disengaged from extension 15.

From the above description the operation of the device will be understood to be as follows: The billets to be treated are successively fed between rolls 1, 2, and 3, by which they are rotated and fed against the point of mandrel 7, where the combined action of said mandrel and rolls effects the piercing of the same. To remove the spiral convolutions formed in the tubes by the above operation said tubes then pass over the supplemental mandrel 11 and between its rolls 8, 9, and 10, the latter continuing the feed of the tubes, and, in conjunction with the working surface 40 of even diameter of said mandrel 11, effectually removing the spiral convolutions in said tubes. When it is desired at the same time to reduce the thickness of the tubes, said supplemental rolls are moved nearer together, thereby reducing the pass between them and mandrel 11, which necessarily effects a corresponding reduction in the external diameters of the tubes without affecting their internal diameters.

The operation of the cooling device for the conical mandrel 7 will be readily understood, the cooling liquid, preferably water, being supplied from a suitable reservoir through pipe 16, extension 15, and pipe 14 and preferably under considerable pressure, the same impinging against the front end of the chamber formed in the mandrel 7, thereby exerting a cooling effect thereon and escaping backward through the shaft 12 and around pipe 14. It will be apparent, however, that unless pipes 14 and 16 can be disconnected the tubes could not pass beyond the rear end of shaft 12, and this we accomplish by providing the angular extension 15 and strap 17, the latter, when engaged with the inclined rear end of extension 15, firmly seating said extension against the rear end

of pipe 14, but when swung upward sufficiently to clear said extension permitting the latter and its pipe 16 to be swung downward or otherwise removed from pipe 14 to permit the passage of a completed tube over the end of shaft 12.

It will be understood that our improved device is equally applicable for use in connection with the piercing of solid billets or in connection with the treatment of hollow tubes to alter the internal or external diameters thereof, as will be readily understood.

Having thus described our invention, what we claim as new, and desire to secure by Letters Patent, is—

1. In apparatus for transforming blanks of metal into tubes, a series of feeding and compression rolls, and a conical piercing-mandrel located between the working faces thereof, in combination with a supplemental mandrel of even diameter, and a series of supplemental feeding and compression rolls operating in conjunction with said supplemental mandrel to engage and act on the tubes after they pass from said piercing-mandrel. 85

2. In apparatus for transforming blanks of metal into tubes, a series of rolls arranged so that no two of their axes lie in the same horizontal plane, said axes being also out of parallel alinement vertically with respect to the line of travel of the blank, and a conical piercing-mandrel located centrally with respect to the adjacent working faces of said rolls, in combination with a supplemental mandrel of even diameter, and a series of supplemental rolls conforming in configuration and arrangement with said first-mentioned rolls and operating in conjunction with said supplemental mandrel to receive and act on the tubes after they pass from said piercing-mandrel. 95

3. In apparatus for transforming blanks of metal into tubes, a series of barrel-shaped rolls arranged so that no two of their axes lie in the same horizontal plane, said axes being also out of parallel alinement vertically with respect to the line of travel of the blank, and a conical piercing-mandrel located centrally with respect to the adjacent working faces of said rolls, in combination with a supplemental mandrel of even diameter, and a series of supplemental rolls conforming in configuration and arrangement with said first-mentioned rolls and operating in conjunction with said supplemental mandrel to receive and act on the tubes after they pass from said piercing-mandrel. 110

4. The combination with a piercing-mandrel formed with an interior chamber, and its supporting-shaft longitudinally apertured to communicate with said chamber, of a liquid-supply tube located within said shaft and of smaller external diameter than the diameter of said aperture in said shaft and open at its inner end, a removable liquid-supply pipe, and means for detachably engaging said pipe with the outer projecting end of said tube. 125

5. The combination with a piercing-man-

drel formed with an interior chamber, and its supporting-shaft longitudinally apertured to communicate with said chamber, of a liquid-supply tube located within said shaft and of 5 smaller external diameter than the diameter of said aperture in said shaft and open at its inner end, a removable liquid-supply pipe, an angular extension on the end of said pipe adapted to seat against the outer projecting 10 end of said tube, and a strap pivoted to said tube and adapted to swing over the end of

said extension to detachably retain the two together.

In testimony whereof we have hereunto set our hands in the presence of two subscribing 15 witnesses.

ELLWOOD IVINS.
WILLIAM GRIFFITHS.
